WATER GUN

Athan Bicos, Mazeika, Kalavriton, Greece

Application November 1, 1948, Serial No. 149,423

Term of patent 14 years

(Cl. D30—1)

To all whom it may concern:

Be it known that I, Athan Bicos, a citizen of the United States, residing at Mazeika, Kalavriton, Greece, have invented a new, original, and ornamental Design for a Water Gun, of which the following is a specification, reference being had to the accompanying drawing, forming part thereof.

In the drawing:

Figure 1 is a side elevational view of a water gun embodying my new design;

Figure 2 is a top plan view thereof;

Figure 3 is a bottom plan view thereof;

Figure 4 is an elevational view of the muzzle end thereof; and

Figure 5 is an elevational view of the breech end thereof.

I claim:

The ornamental design for a water gun, as shown.

ATHAN BICOS.
